UNITED STATES PATENT OFFICE.

HORACE H. NEWMARK, OF LOUISVILLE, KENTUCKY.

DISPLAY APPARATUS.

1,246,454.

Specification of Letters Patent. Patented Nov. 13, 1917.

Application filed August 25, 1916. Serial No. 116,833.

To all whom it may concern:

Be it known that I, HORACE H. NEWMARK, a citizen of the United States, residing at Louisville, in the county of Jefferson and

5 State of Kentucky, have invented certain new and useful Improvements in Display Apparatus, of which the following is a specification.

This invention has for its object to improve 10 the display in show windows of stores, and to this end it consists in a floor for the window, which floor is made up of a series of traveling sections by which the articles to be displayed are carried to different parts 15 of the window, thus giving a more uniform display of such articles.

In order that the invention may be better understood, reference is had to the accompanying drawing forming a part of this 20 specification, in which the preferred embodiment of the invention has been shown, it being understood that various changes and modifications may be made without departure from the spirit and scope of the invention as claimed hereinafter.

In the drawing—

Figure 1 is a plan view of the device;

Figs. 2 and 3 are sections on the lines 2—2 and 3—3, respectively of Fig. 1, and

30 Fig. 4 is a plan view showing a modification.

Referring specifically to the drawing, 10 denotes a rectangular frame of channel irons which forms the supporting frame of a series of independent and separately shiftable floor sections. This frame is suitably built into a store window or other place of display for articles of merchandise and the like. The floor sections are arranged in 15 two parallel rows, the sections of one row being shown at 11, and those of the other row at 12. The sections of the two rows abut and they are all of the same dimensions, and the number of sections in each 20 row is such that they do not completely fill the frame 10, there being left at the end of each row a space corresponding in dimensions to that of one of the respective sections. This space at the end of the row of 25 sections 11 is shown at 13, and the space at the end of the row 12 is shown at 14. It will be noted that the open spaces are not both at the same end of the frame, but one of them is at one end, and the other is located at the other end. 55

The articles to be displayed are suitably mounted on the floor sections 11 and 12, and by shifting said sections in a manner to be presently described, such articles are carried around in the window, whereby a better and more uniform display is obtained. 60

The rows of sections 11 and 12 are shiftable lengthwise in the frame 10, in opposite directions as shown by the arrows in Fig. 1. Assuming the sections to be positioned as shown in Fig. 1, the row of sections 11 moves to the right until the end section of said row next to the open space 13 enters said space. At the same time, the row of sections 12 moves to the left until the end section of said row next to the open space 14 enters this space. The open spaces at one end of each row have now been reversed, there being now an open space at the left end of the row of sections 11 and one at the right end of the row of sections 12. The section of the row of sections 11, at the right end thereof, now moves laterally into the space at the right end of the row of sections 12, and the section of the row of sections 12, at the left end thereof, moves laterally into the space at the left end of the row of sections 11. Thus, it will be seen that the spaces 13 and 14 are now again unoccupied, and the two rows are in the same position as at the commencement of the operation, except that they have been shifted lengthwise, and one of the end sections of each row has been transferred to the other row. These operations are repeated, and when a number of shifts have been made corresponding to the number of sections in the respective rows, the positions of the rows will be reversed, the rear row having been brought to the front and the front row to the rear. The longitudinal movement of course ceases when the lateral shift of the end sections commences, and when the transfer of the end sections from one row to the other has been made, the longitudinal movement is resumed. It will 70

therefore be seen that the sections have a continuous step-by-step orbital movement, thus bringing all the articles, one after the other, into display position in front of the window.

Inside the frame 10 is a guide rail 15 for supporting the inner edges of the floor sections, and at the bottom of the frame is a flooring 16 over which the sections slide.

13 The following mechanism is provided for shifting the floor sections:

On the bottom of each floor section are two depending abutments 17 and 18, respectively, which pass through slots 19 in the flooring 16. These slots run longitudinally to permit the longitudinal movement of the sections, and at the ends of the rows, the flooring has transverse slots 20 joining the ends of the longitudinal slots to accommodate the abutments when the sections are shifted laterally. At the left end of the row of sections 11, beneath the flooring 16, are mounted two laterally spaced sprocket wheels 21 over which passes a chain 22 which also passes over a sprocket wheel 23 located beneath the sprocket wheels 21. The chain has a projecting finger 24 located to intercept the abutments 17 on the floor sections. The two sprocket wheels 21 are located to give the chain 22 a top horizontal run extending in the direction of the length of the row of sections 11. This portion of the chain 22 is so positioned that when the finger 24 reaches the same it engages the

35 abutment 17 of the section 11 at the left end of the row, and as the finger moves along the horizontal top run of the chain, the entire row of sections 11 is pushed toward the right, the spacing of the sprocket 40 wheels 21 being such that the row is shifted the required distance, the shifting movement ceasing when the finger leaves the top run of the chain and slips off the abutment.

The lateral shift of the sections 12, when 45 they arrive at the left end of this row and are to be transferred into the space at the left end of the row of sections 11 left open by the shift toward the right of said sections 11, is effected by the following means:

50 At the left end of the row of sections 12, under the flooring 16, are mounted two laterally spaced sprocket wheels 25 over which passes a chain 26 which latter is also trained over a sprocket wheel 27 located beneath the sprocket wheels 25. The chain 26 has a projecting finger 29 located to intercept the abutments 18 of the floor sections. The two sprocket wheels 25 are located to give the chain 26 a top horizontal run extending transversely of the rows of floor sections, or at a right angle to the top run of the chain 22. This top run of the chain 26 is so positioned that when the finger 28 reaches the same it engages the abutment 60 18 of the section 12 at the left end of this

row, and as the finger moves along the top horizontal run of the chain, the end section is shifted across to the left end of the row of sections 11.

The longitudinal and lateral shifting mechanism hereinbefore described is, of course, duplicated at the right end of the rows of floor sections.

The sprocket wheel 23 is on a shaft 29 and the sprocket wheel 27 is on a shaft 30. These 75 two shafts are at a right angle to each other and they are operatively connected by a bevel gearing 31. The shafts 29 at the respective ends of the rows of floor sections may be driven from a shaft 32 through 80 bevel gears 33.

The chains 22 and 26 are driven continuously, but the fingers 24 and 28 are so arranged that they engage the abutments 17 and 18 alternately. It will therefore be evident that the longitudinal and lateral shifting movements occur in alternate order.

Fig. 4 shows a modification in which a series of independent floor sections 34 are attached to an endless chain or belt 37 by 90 clips 38. The chain passes over sprocket wheels 39 the shafts 40 of which stand vertically so that the spacing of the two parallel runs of the chain is horizontal and the floor sections are supported in horizontal position. 95 Any suitable means, connected to one of the shafts 40, may be provided for driving the chain.

I claim:

1. A display apparatus comprising a series of independent and separate article-supporting sections arranged horizontally and in parallel rows, a support on which the sections are slidably mounted, the sections of the respective rows abutting, means engageable with the end sections of the respective rows for shifting said rows longitudinally on their support in opposite directions for a distance to project the sections at opposite ends of the respective rows beyond the adjacent row, and means for shifting said projecting sections laterally from one row to the other.

2. A display apparatus comprising a series of independent and separate article-supporting sections arranged horizontally and in parallel rows, the sections of the respective rows abutting, a support on which the sections are mounted, abutments depending from the sections, the support having longitudinal rows of slots and transverse slots connecting the ends of the longitudinal rows of slots, through which slots the abutments extend, means engagable with one of the abutments of the end sections of the respective rows for shifting said rows longitudinally in opposite directions for a distance to project the sections at opposite ends of the respective rows beyond the adjacent row, and means engageable with an

abutment of the projecting sections for shifting said sections laterally from one row to the other.

3. A display apparatus comprising a series of independent and separate article-supporting sections arranged horizontally and in parallel rows, the sections of the respective rows abutting, a support on which the sections are mounted, abutments depending from the sections, means engageable with one of the abutments of the end sections of the respective rows for shifting said rows longitudinally in opposite directions for a distance to project the sections at opposite ends of the respective rows beyond the adjacent row, and means engageable with an abutment of the projecting sections for shifting said sections laterally from one row to the other.

20 4. A display apparatus comprising a series of independent and separate article-supporting sections arranged horizontally and in parallel rows, the sections of the respective rows abutting, a support on which the sections are mounted, abutments depend-

ing from the sections, means engageable with one of the abutments of the end sections of the respective rows for shifting said rows longitudinally in opposite directions for a distance to project the sections at opposite ends of the respective rows beyond the adjacent row, and means engageable with an abutment of the projecting sections for shifting said sections laterally from one row to the other, the aforesaid longitudinal shifting means being horizontally traveling elements running in opposite directions and lengthwise of the rows, and having projecting fingers to engage the first mentioned abutments, and the lateral shifting means 30 being horizontally traveling elements running in opposite directions and transversely of the rows, and having projecting fingers to engage the second mentioned abutments.

25 In testimony whereof I affix my signature in the presence of two witnesses.

HORACE H. NEWMARK.
